UNITED STATES PATENT OFFICE.

LAURITS HENRIK NIELSEN, OF KOLDING, DENMARK, ASSIGNOR TO THE OSBORN MANUFACTURING COMPANY, OF CLEVELAND, OHIO, A CORPORATION OF OHIO.

CYLINDRICAL OR RING-SHAPED BRUSH.

Application filed April 18, 1921. Serial No. 462,431.

To all whom it may concern:

Be it known that I, LAURITS HENRIK NIELSEN, a subject of the King of Denmark, and a resident of Kolding, Denmark, have 5 invented a new and useful Improvement in Cylindrical or Ring-Shaped Brushes, of which the following is a specification, the principle of the invention being herein explained, and the best mode in which I have 10 contemplated applying that principle so as to distinguish it from other inventions.

The present improvements relate to that type of industrial brushes generally known as rotary brushes, which are made up of 15 several layers or sections, firmly held together and mounted on a shaft through the medium of a suitable base or hub. One object of the invention is the provision of a brush of this type, in which the sections 20 may be readily and inexpensively constructed out of any of the usual materials. Another object is to provide a convenient and satisfactory manner for combining an assemblage of such sections into a unitary structure, in which the brush material is not only 25 firmly held but properly distributed and supported so as to give maximum service. Still another object is the provision of a 30 unique form of base or mounting for a brush of the general type in question, and particularly one of the special construction hereinbefore referred to.

To the accomplishment of the foregoing and related ends, said invention, then, 35 consists of the means hereinafter fully described and particularly pointed out in the claims, the annexed drawing and the following description setting forth in detail certain mechanism embodying the invention, such disclosed means constituting, however, but several of various mechanical forms in which the principle of the invention may be used.

In said annexed drawing:—

40 Figs. 1 to 3, inclusive, illustrate in cross-section the appearance of an individual brush section in successive stages of manufacture; Fig. 4 is a broken side elevation of such section in the stage of manufacture illustrated in Fig. 3; Fig. 5 is a cross-section of a completely assembled brush showing more particularly the manner in which the brush sections are mounted on the holder therefor provided; Fig. 6 is a similar sec-

tion showing a modification in the construction of such holder; Fig. 7 is a view similar to Fig. 4, showing a modification in the construction of the individual sections; and Fig. 8 is another view similar to Fig. 5, but showing a different form of base, as well as a modification in the manner in which the assembled sections are secured together.

A characteristic feature in the construction of the component layers, sections or brush rings of my improved rotary brush is 65 the inclusion of suitable rings of pasteboard or equivalent fibrous material as spacing pieces between the bent fibrous material which constitutes the operative part of the brush, similar rings being also used as spacing members between adjacent sections. Another characteristic feature is the use of one or more rows of nails that are driven transversely into the assembled sections composing the brush, such nails being driven 70 in from both sides so as to penetrate the successive rings of pasteboard or like material, and being spaced so closely as to prevent the fibrous material from being torn 75 loose or drawn out from the brush when the latter is in use.

In the illustrative section or layer, as illustrated in Figs. 1 to 4, inclusive, it will be noted that the fibrous material 2 is bent around a ring formed wire 1 into open U-shape, the free ends of the material extending radially outward from such ring. Between the respective outwardly bent ends of brush material there is placed a pasteboard ring 3 of approximately the same thickness 80 as said wire 1, such brush material being thereupon pressed against such ring and held solidly in place by means of one or more rows of stitching 4.

The manner in which the brush material 95 is assembled on the wire ring 1, and then pressed against the pasteboard ring and stitched to the latter forms no part of the present invention, but it may be explained that special devices may be utilized to advantage in this connection whereby the section may be thus preliminarily formed and then placed under a sewing machine in order to stitch the brush material and the pasteboard ring together. It will be observed that the stitching 4 is applied directly to the brush material without using any other means for holding the same in 100 105

place or afterwards bending same into rotary shape; also that in place of such stitching 4, one or more rows of steel wire staples, or specially bent steel pieces 12, may be employed as shown in Fig. 7, such staples preferably over-lapping each other so as to give the same effect as a continuous stitching.

Due to the fact that the ring-shaped pasteboard or fibrous inlay 3 is of approximately 10 the same thickness as the winding wire or ring 1, such inlay serves to equalize the pressure when a plurality of sections are put together, and prevents such pressure from being localized against the successive wire 15 rings. With sections of the construction described it is possible to assemble a rotary brush of any desired thickness, and the method of construction is equally adaptable to sections of different diameters.

20 In assembling a plurality of sections to form a rotary brush of desired thickness, I place between such sections pasteboard rings 5 as shown in Fig. 5, these rings being of slightly larger diameter internally than the 25 brush sections. Said rings are first dipped in glue before being laid between such sections, which are then pressed together, and when dried constitute, in effect, a unitary structure. In order to fill out the spaces 30 that are left between the interior parts of said rings and the brush sections, when thus assembled, a layer 6 of molten pitch may be applied in the central opening so as to form a smooth cylindrical wall and further assist 35 in binding the sections together. I may also drive one or more circular rows of broad-head nails 13 through the assembled body of brush sections, as shown in Fig. 8, such nails being thus driven from opposite 40 sides adjacent to the wire rings 1, so as to penetrate more or less completely the successive pasteboard rings 3 and 5. These 45 nails serve to strengthen the base of the brush and more firmly secure the brush material to such base, as will be readily apparent.

For the purpose of mounting the finished brush on the shaft or arbor I have designed 50 the special mounting or holder shown in Fig. 5, such mounting comprising a transversely split band 7, and two co-operating side plates or rings 8. The inner faces of the latter are cut away or otherwise formed to present conical bearings that contact with 55 the respective sides of the band 7 so that when side plates are drawn together said band will be expanded against the cylindrical wall of the central opening in the brush, thereby binding such band and brush together and forming a compact unit. At 60 the same time the brush is prevented from turning on the mounting when in use.

A brush constructed in the fashion hereinbefore described may of course be mounted 65 on other kinds of hubs than the special

one just described. Thus, as shown in Fig. 6, the hub may consist of two complementary wooden rings 10 with laterally projecting flanges, between which the brush is held, said rings being drawn together by nails or 70 screws 11. Supplemental flat metal rings 9 are also shown in the figure in question as projecting laterally beyond the flanges on the wooden rings 10 so as to afford correspondingly increased support for the sides 75 of the brush. The use, however, of these rings is optional. Thus, in Fig. 8 I show the brush as directly held between the flanges on two wooden rings 14 that constitute the hub, said rings here taking the form 80 merely of side plates similar to the metal side plates 8 shown in Fig. 5. As in the case of hub sections of Fig. 6, so the rings 14 in Fig. 8 will be held together with nails or 85 equivalent securing means.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. A rotary brush section comprising a 90 base ring, brush material looped upon said ring, a flat ring inserted between such looped material adjacent said ring, and fastening means for securing such material to said flat ring.

2. A rotary brush section comprising a 95 base ring, brush material looped upon said ring, a flat ring inserted between such looped material adjacent said ring, and stitching passing through such material and flat ring.

3. In a rotary brush, the combination of 100 a plurality of sections, each comprising a base element, brush material looped upon said element, a fastening means securing such material to said element; and flat spacing rings interposed between successive sections, said rings and sections being secured together.

4. In a rotary brush, the combination of 105 a plurality of sections, each comprising a base element, brush material looped upon said element, and fastening means securing such material to said element; and flat spacing rings interposed between successive sections, said rings and sections being glued together.

5. In a rotary brush, the combination of 110 a plurality of sections, each comprising a base element, brush material looped upon said element, and fastening means securing such material to said element; and flat spacing rings of larger internal diameter than 115 said sections interposed between successive sections, said rings and sections being glued together, and the spaces left in the central 120

opening in such assembled sections and rings being filled with plastic material adapted to set upon standing.

6. In a rotary brush, the combination of a plurality of sections, each comprising a base element, brush material looped upon said element, and fastening means securing such material to said element; flat spacing

rings interposed between successive sections, said rings and sections being glued together; and a circle of nails transversely driven into such assembled sections and rings. ¹⁰

Signed by me, this 13th day of April, 1921.

LAURITS HENRIK NIELSEN.
